COMBINED KNIFE, FORK, AND CONTAINER OPENER

Samuel L. Gerson, 229B Monroe Park Apts.,
Thomas Drive, Wilmington, Del.

Filed May 7, 1958, Ser. No. 50,779

Term of patent 14 years

(Cl. D44—29)

Fig. 1 is a side elevational view of a combined knife, fork and container opener showing my new design;

Fig. 2 is a bottom edge view thereof; and

Fig. 3 is a perspective view thereof.

I claim:

The ornamental design for a combined knife, fork and container opener, substantially as shown.
